(57) **CLAIM**

The ornamental design for a lamp, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a top plan view

FIG. 1.2 is a top/side perspective view of the lamp in FIG. 1.1:

FIG. 1.3 is a side view of the lamp of FIG. 1.1; and FIG. 1.4 is a bottom perspective view of the lamp of FIG. 1.1.

The broken lines in the drawings depict portions of the lamp that form no part of the claimed design.
